UNITED STATES PATENT OFFICE.

HORACE H. BURDETT, OF HOPEDALE, MASSACHUSETTS, ASSIGNOR TO DRAPER CORPORATION, OF HOPEDALE, MASSACHUSETTS, A CORPORATION OF MAINE.

BUILDER MECHANISM FOR YARN SPINNING OR WINDING MACHINES.

Application filed October 21, 1926. Serial No. 143,119.

This invention relates to builder mechanisms for yarn winding or spinning machines and is more particularly directed to builder mechanisms wherein a bunch builder attachment is employed to place upon the filling carriers or bobbins a reserve supply of filling.

It is now the common practice to provide filling carriers or bobbins with a reserve supply of filling, sometimes termed a "bunch," to insure that a complete length of filling be laid in the shed on the last pick of the shuttle before replenishment.

The present invention is a further development of the builder mechanisms shown and described in the prior patents to Horace H. Burdett, No. 1,556,814, dated October 13, 1925; No. 1,556,815, dated October 13, 1925, and No. 1,579,190, dated March 30, 1926.

In ordinary practice the yarn guiding means which directs the yarn to the filling carriers or bobbins is depressed on the completion of a series of wound bobbins to permit the full bobbins to be doffed and be replaced by empty filling carriers or bobbins, and when this has been done and a "bunch" is to be placed upon the filling carriers or bobbins, it is desirable that the bunch building mechanism be placed in operative position to wind the "bunch" when the machine is first started and on completion of the "bunch" to pass out of operative position in order that the regular service traverse may be resumed for completion of the wind.

During the winding operation, the yarn guide or ring rail is progressively raised, so that on the completion of the wind it is at its upper position, and after the full bobbins have been doffed and the empty bobbins placed in the machine, it is usual to "wind back" in order to commence the windings at a point adjacent the heads of the bobbins. In the Burdett Patent, No. 1,579,190, means are provided which utilize the "winding back" operation to bring into operative position a bunch builder mechanism which, upon completion of the bunch, will automatically go out of operation to permit regular service to continue in the completion of the winds.

In builder mechanisms of the type shown and described in the Burdett patent above noted, it is desirable that the bunch wind shall commence at some predetermined point on the successive series of bobbins or filling

carriers, because the reserve supply of yarn or "bunch" constitutes waste when the depleted filling carriers or bobbins are ejected from the loom, and the knowledge of what such waste shall be in any case is important.

One of the features of the present invention consists in providing means whereby the worm which cooperates with the bunch building device to form the bunch shall be returned to a predetermined rotative position automatically when the bunch is completed, with the result that successive series of bobbins shall be provided with bunches, the winds of which commence at the same part of the bobbin.

The practice in some mills, owing to the character of the spinning or winding machine or its speed of operation or the character of yarn employed, requires that the predetermined point at which the worm shall come to rest when moved out of bunch building relation with the bunch building device shall be capable of variation, and another important feature of the present invention, therefore, consists in providing means which will not only return the worm to a predetermined position when it goes out of action, but which shall be capable of varying the predetermined point to which the worm is turned.

The invention and new combination of parts and novel features thereof will best be made clear from the following description and the accompanying drawings of one good form of the invention.

In the drawings:

Fig. 1 is a perspective view of a builder mechanism containing the present invention, some of the parts being broken away;

Fig. 2 is an end view of the worm;

Fig. 3 is an enlarged section on the line 3-3 of Fig. 1, some of the parts being omitted for clearness of illustration, and showing more particularly the means for returning the worm to the desired predetermined rotative position when it is moved out of bunch building relation with the bunch building device or disk;

Fig. 4 is a detail perspective view of one means for moving the worm to the predetermined rotative position; and

Fig. 5 is a side elevation of the worm on an enlarged scale.

In accordance with the illustrated embodiment

ment of the present invention, the builder mechanism is of the general type shown and described in the Burdett Patent, No. 1,579,190, wherein the "winding back" operation is utilized for positioning parts to cause the worm to move into operative bunch building relation with the bunch building device or disk when the builder arm is depressed, but, as will be apparent, the means for effecting rotative movement of the worm to the desired predetermined position may be utilized in other forms of bunch building mechanisms.

The yarn spinning or winding machine 15 may be of the general character shown and described in the Burdett patent last before mentioned, and is not herein shown because the details thereof form no essential part of the present invention and are fully described 20 and shown in the Burdett patent, to which reference may be had.

The builder mechanism comprises the usual main builder cam 1 supported for rotative movement upon the machine frame 25 and the builder arm 2 pivoted at its rear end portion to the machine frame and carrying the follower or roll 3 adapted to ride upon the peripheral cam portion of the main builder cam 1 during the main traverse 30 wind, and such parts may be substantially the same as in the Burdett patent above noted.

Mounted upon the builder arm 2 is the gear or pinion 4, the teeth of which are engaged by the usual worm 5 secured to the shaft 6 which is itself mounted in bearings 7 carried by the builder arm, and the outer end portion of the shaft 6 carries the usual pick wheel 8 which, as usual in this type of machine, is given a step-by-step movement during the up and down movement of the builder arm to operate the gear 4 which is connected by flexible means to the yarn guide or ring rail. Secured to the gear 4 is 45 the winding drum 9 to which is connected at 10 the chain or flexible connection 11 which extends over the usual guiding means, as indicated in the Burdett Patent, No. 1,579,190, and is secured to the usual segment for controlling the movement of the ring rail. These features may all be of 50 usual construction, and as they are fully shown and described in the Burdett patent, further illustration and description thereof 55 appears unnecessary.

The builder arm 2 carries a bracket 12 which may be secured to the builder arm by means of the bolts 13 which pass through openings 14 in the face of the bracket, 60 whereby the bracket itself may be adjusted relative to the builder arm by means of the adjusting bolts 15, and these parts may be substantially the same as in the Burdett patent above mentioned.

65 Mounted in bearings 16 extending later-

ally relative to the builder arm 2 is the shaft 17 on which is mounted a finger or arm 18 held in position on the shaft 17 by means of the end collars 19 and 20. The finger or arm 18 is formed with a cam or bevelled 70 surface 21 and is normally under the influence of a spring 22 which acts to maintain the arm or finger 18 in its upwardly extending position, as indicated in Fig. 1. Secured to the face of the drum 9 is a pin 23 which, 75 on "winding back" engages the bevelled or cam face of the arm or finger 18 and moves said arm or finger outwardly, and in order to limit the upward or initial position of the finger or arm 18 a stop 24 is provided to engage a suitable shoulder on the collar 20. These parts may also be the same as in the Burdett Patent, No. 1,579,190, when the bunch builder mechanism is associated with the "winding back" devices for throwing 80 the bunch builder mechanism into bunch building relation with the bunch building device.

Extending from the shaft 17 is an arm 25 which bears upon the outer end portion of a worm positioning pin 26 mounted for sliding movement in a sleeve 27 carried by the downwardly extending arm 28 which may be appropriately secured to or formed as part of the bracket 12.

Mounted for sliding movement laterally of the builder arm 2 is the worm 29 carried by a rod or support 30 which is itself adjustably secured to the bracket 12 by threaded connection with the nut 31. The rod or support 30 is provided with a shoulder 32 and the hub portion 33 of the worm has a cooperating shoulder 34 for limiting the outward movement of the worm under the actuation of the worm positioning pin 26. These parts may also be similar to the corresponding parts shown and described in the Burdett patent.

Mounted for cooperation with the worm 29 is a bunch building device 35 which, in the present instance of the invention, comprises a disk mounted for rotative movement and actuated from a suitable going part of the machine. In the present instance, the bunch building device or disk 35 may be secured to the main builder cam 1 as more fully shown and described in the Burdett patent.

From the construction thus far described and as more fully elucidated in the Burdett patent, it will be obvious that during the regular building traverse the follower 3 rides upon the peripheral portion of the main builder cam 1 to lay the yarn upon the filling carriers or bobbins by regular traverse, and as the builder arm 2 is actuated, the winding drum 9 lets back upon the flexible connection with the yarn guide or ring rail through the pick mechanism, as usual in this type of machine. When a

set of bobbins has been completely filled with yarn, the ring rail or yarn guide is at its upper position and the machine stops; whereupon the yarn guide or ring rail is lowered for doffing and, of course, the builder arm 2 is lowered. Before commencing to wind yarn upon the fresh set of empty filling carriers or bobbins, the machine attendant will "wind back"; that is, he will turn the shaft 6 to rotate the winding drum 9 to lower the ring rail, and, as this is done, the pin 23 acting upon the finger or arm 18 will cause the worm 29 to move into its outer or bunch building relation with the bunch building device or disk 35, provided the attendant has not lifted the builder arm so as to bring the outer face of the worm into contact with the adjacent face of the bunch building device or disk. The machine attendant frequently raises the builder arm to more conveniently "wind back" and in such case the finger or arm 18 will be moved outwardly as before, but since the worm cannot move outwardly into bunch building position at this time, the spring 21 is placed under tension, so that upon the attendant letting go of the builder arm it will drop to lower the worm 29 below the peripheral portion of the bunch building device or disk; whereupon, the worm will move to its bunch building position in contact with the periphery of the bunch building device or disk 35, with the result that upon starting to wind a fresh set of bobbins, the bunch building mechanism will first lay a reserve supply upon the bobbins, and finally the worm will be moved laterally out of bunch building position to permit regular service traverse to be resumed.

As hereinbefore indicated, it is desirable that the worm be rotatably positioned at such times to bring the same point of the periphery of the worm into contact with the bunch building device or disk when the worm is again moved into bunch building position, and as the practice in different mills requires that the predetermined rotative position of the worm shall be different from what it is in other mills, means for returning the worm to its predetermined position is rendered variable in accordance with the present invention.

As shown, the worm 29 is provided with a faced recess 36 to receive the worm rotatable means which, as shown in the present instance, comprises a weight. As indicated in Figs. 3 and 4, the weight is formed as a disk 37 having an overweighted portion 38 at one side of its axis and the disk is secured to the worm by appropriate means such, for instance, as the screw bolts 39. There may be a number of such securing bolts, with the result that the weighted disk 37 may be adjusted rotatably relative to the worm and then secured in adjusted position.

The disk 37 has a flange portion 40 which rests upon the face 41 of the recessed portion of the worm, with the result that the inner face portion of the disk presents a substantially smooth surface upon which bears the worm positioning pin 26. The preferred manner for securing the weighted disk 37 to the worm is shown as comprising the threaded lugs 42 into the threads of which the securing bolts 39 extend, and as the threaded recesses in the disks do not extend to the exposed surface thereof, the worm positioning pin bears upon the substantially smooth surface of the exposed portion of the disk.

In the present instance of the invention, the weighted portion 38 of the disk is shown as extending substantially half way around the disk, but, obviously, this may be otherwise, the essentials in this respect being that the worm be provided with a weighted portion, where a weight is used, so that when the worm is moved out of bunch building relation with the bunch building device or disk 35, the weight will act automatically to move the worm into the predetermined rotative position desired to thereby insure that when the worm is again moved into bunch building relation with the bunch building device or disk, the same peripheral portion of the worm will be utilized in starting the bunch on successive series of bobbins.

As more fully pointed out in the Burdett patent to which attention has been called, the size of the bunch, that is, the number of windings which constitute the reserve supply or "bunch" may be varied by adjusting the rod or support 30 which supports the worm, and as the reserve supply or "bunch" is initiated at the same peripheral point of the worm, on starting to wind successive series of bobbins or filling carriers it follows that the "bunch" on such successive series of bobbins will commence at the same point and contain the same amount of yarn.

As a worm is moved laterally by the bunch building device or disk 35 by which the worm is rotated during the bunch building operation, any sudden disengagement of the worm from the bunch building device or disk might result in a "jump" of the yarn guide or ring rail, and cause yarn breakage. To obviate this, the outer or final end portion of the worm is formed into a scroll 43 which gradually approaches the central portion or axis of the worm, with the result that as the worm is moved laterally by the bunch building device and finally presents the scroll thereto, the ring rail will move with ease and without jump to bring the follower 3 into contact with the main builder cam.

The weight 38 constitutes a good practical form of means of simple character for insuring rotative movement of the worm into a predetermined position when it is moved

out of bunch building engagement with the bunch building device or disk, and by reason of the fact that it is adjustable to different positions relative to the worm, such predetermined point may be varied to suit the particular conditions of the mill or the spinning or winding machine in which the bunch building device is employed.

During the bunch building operation, the peripheral portion of the disk 35 will ride in the depressions in the worm and cause rotative movement of the latter and also lateral movement during rotation of the worm so that on completion of the "bunch" the worm will be moved laterally out of bunch building relation with the disk; whereupon, the weight 38, or other worm actuating means, will return the worm rotatively into a predetermined position to commence the next bunch windings on a series of bobbins at the same point where the previous windings had commenced.

What is claimed is:

1. In a builder mechanism, the combination of a main builder cam, a builder arm having a follower for engagement with the main builder cam during main service windings, a rotating bunch builder device, a worm carried by the builder arm for cooperation with said device in building the bunch and moved by the rotating device out of bunch building position on completion of the bunch, and means acting independently of the rotating bunch builder device for rotating the worm into a predetermined rotative position when moved out of engagement with and free from the rotating device.

2. In a builder mechanism, the combination of a main builder cam, a builder arm having a follower for engagement with the main builder cam during main service windings, a rotating bunch builder device, a worm carried by the builder arm for cooperation with said device in building the bunch and moved by the rotating device out of bunch building position on completion of the bunch, and means acting independently of the rotating bunch builder device for effecting rotative movement of the worm in one or the opposite direction into a predetermined position when not in contact with the rotating device.

3. In a builder mechanism, the combination of a main builder cam, a builder arm having a follower for engagement with the main builder cam during main service windings, a rotating bunch builder device, a worm carried by the builder arm for cooperation with said device in building the bunch and moved by the rotating device out of bunch building position on completion of the bunch, and a weight connected to the worm for rotating the worm into a predetermined position when moved from bunch building relation with said rotating device.

4. In a builder mechanism, the combination of a main builder cam, a builder arm, a bunch builder member, a worm carried by the builder arm for cooperation with the disk in building the bunch, and a weight for relatively turning the worm and bunch builder member into predetermined relation when the worm and bunch builder member are disengaged.

5. In a builder mechanism, the combination of a main builder cam, a builder arm, a bunch builder disk, a worm carried by the builder arm for cooperation with the disk in building the bunch, means connected with the worm for turning it into a predetermined position when moved from bunch building relation with the disk, and devices for changing the extent of movement of the worm effected by said means to vary the predetermined position to which the worm is moved.

6. In a builder mechanism, the combination of the main builder cam, the builder arm, a bunch builder disk, means for rotating the disk, a worm carried by the builder arm for cooperation with the disk in building a bunch, a weight for rotating the worm when moved from bunch building relation with the disk, and means for adjusting the relation of the weight and worm.

7. In a builder mechanism, the combination of the main builder cam, the builder arm, a bunch builder device, means for rotating the main builder cam and bunch builder device, a worm carried by the builder arm for cooperation with the bunch builder device in building the bunch and having a weighted portion for turning the worm automatically into a predetermined position when out of bunch building position.

8. In a builder mechanism, the combination of the main builder cam, the builder arm, a bunch builder device, means for rotating the main builder cam and bunch builder device, a worm carried by the builder arm for cooperation with the bunch builder device in building the bunch and having a weighted portion for turning the worm automatically into a predetermined position when out of bunch building position, and means for adjusting the weighted portion of the worm to vary its rotative position of rest.

9. In a builder mechanism for spinning or winding machines, the combination of the main builder cam and builder arm, a rotary bunch builder device, a worm mounted on the builder arm for cooperation with the bunch builder device, and a weight for rotatively relating the worm and bunch builder device into a predetermined position when the worm and bunch builder device are disengaged on completion of the bunch.

10. In a builder mechanism for spinning or winding machines, the combination of the

main builder cam and builder arm, a rotary bunch builder device, a worm mounted on the builder arm for cooperation with the bunch builder device and movable thereby, a weight for automatically turning the worm into predetermined position when moved from bunch building position, and means for

changing the position of the weight for varying the predetermined position assumed by the worm.

In testimony whereof, I have signed my name to this specification.

HORACE H. BURDETT.
